ALUMINUM CONTAINER CRUSHER

Joe R. Smith, 509 Brookside Circle,
Maitland, Fla. 32751

Filed Mar. 6, 1975, Ser. No. 555,979

Term of patent 14 years

Int. Cl. D15—99

U.S. Cl. D55—1 F

Fig. 1.

Fig. 2.

FIG. 1 is a perspective side view of an aluminum container crusher showing my new design; and

FIG. 2 is a perspective side view of the opposite side thereof, with the upper arm in an alternate position.

I claim:

The ornamental design for an aluminum container crusher, as shown and described.
